(57) **CLAIM**

The ornamental design for a case, as shown and described.

DESCRIPTION

FIG. 1 is a front isometric view of a case showing our new design;
FIG. 2 is a rear isometric view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken line that defines the large unshaded rectangular region on the front of the case represents a boundary of the claimed design. The broken lines immediately adjacent the claimed surfaces also represent boundaries of the claimed design. The broken lines and unshaded surfaces bounded by broken lines form no part of the claimed design.
